UNITED STATES PATENT AND TRADEMARK OFFICE
CERTIFICATE OF CORRECTION

PATENT NO. : Des. 390,799
DATED : February 17, 1998
INVENTOR(S) : Greg S. Uptegraph

It is certified that error appears in the above-identified patent and that said Letters Patent is hereby corrected as shown below:

On the title page, immediately above "[57] Claim", please insert:

--

Preamble

The characteristic feature of the design resides in the ornamental display of elapsing time. Hours and minutes are digitally and ornamentally displayed. Seconds are ornamentally displayed with peripheral markers that disappear sequentially as time elapses.

The structure depicted in the drawings in broken lines forms no part of the design.--

Signed and Sealed this
Fourth Day of August, 1998
